PUSH BAR AND LATCH FOR SWINGING CLOSURES

Henry K. Meis, Tecumseh, Okla.

Application November 24, 1933, Serial No. 699,604

4 Claims. (Cl. 292—67)

The invention relates to devices adapted to be mounted on screen doors and the like and providing a push bar for opening the door and a keeper means to automatically catch and hold the door in closed position, means being also provided to fixedly latch the door, said means co-operating with the push bar or bolt.

A further object of the invention is the provision of a device adapted to be mounted on a swinging closure and its frame comprising a bar slidably mounted relatively to the closure and adapted to coact with a keeper on the frame to hold the door in fixed and latched position, a swinging keeper member being also provided on the door frame and engageable with the bar or bolt when the door is closed and moving inwardly of the door beyond the center of gravity to hold the door in a closed position against casual displacement, yielding means being provided to permit the keeper member to swing and its free end to describe an arc while engaged with the bar or bolt.

The invention will be described in detail hereinafter and will be found illustrated in the accompanying drawings, in which

Figure 1 is a fragmentary view of the inside of a screen door and its frame showing a preferred form of the push bar and latch in position thereon, parts broken away and in section.

Figure 2 is a horizontal sectional view taken on the plane indicated by the line 2—2 of Figure 1.

Figures 3 and 4 are sectional details on planes indicated by the lines 3—3, and 4—4, of Figure 1.

Figure 5 is a fragmentary sectional view on a plane indicated by the line 5—5 of Figure 4.

Figure 6 is a fragmentary view of a screen door and frame showing a modified form of latching means.

Figures 7 and 8 are vertical sectional views on planes indicated by the lines 7—7, and 8—8, respectively, of Figure 6, and

Figure 9 is a horizontal sectional view on a plane indicated by the line 9—9 of Figure 6.

In the drawings similar reference characters are used to designate corresponding parts in all the views.

For the purpose of illustrating the application of the invention, a screen door and its frame have been selected, although it will be apparent that the device may be used with any swinging closure, the screen door being designated at 10 and the frame designated 11. Secured to the door 10 is an L-shaped bracket 12 and a U-shaped bracket 13, the L-shaped bracket being provided with an opening 14 to receive a bolt or bar 15, said bolt

or bar being supported in the U-shaped bracket 13, and is slidably mounted relatively to said bracket and also pivotally mounted relatively to the bracket 12. Secured in the bracket 13 is a pin or bolt 16 that also traverses elongated openings 17 in the bar 15, and mounted on the pin or bolt 16 is an expansible coil spring 18 that normally holds the bolt or bar 15 from swinging movement, as hereinbefore described, and also frictionally holds the bolt or bar from sliding movement relatively to the brackets 12 and 13.

The projecting arm of the bracket 12 may also be utilized as shown in the drawings to engage one end of spring 19 having its other end engaged as shown at 20 to the adjacent side of the frame 11, said spring to return the door to a closed position after being opened.

As shown in the drawings, the bolt or bar 15 is tubular, and the frame 11 is provided with a headed stud 20 projecting from the frame and adapted to engage in the adjacent end of the bolt when slid relatively to the brackets 12 and 13, this providing a fixed latching means for holding the door in closed position.

An automatic latching means is also provided and operates in cooperation with the bolt or bar 15, said automatic latching means comprising a swinging keeper including an arm 21 pivotally mounted on a plate 22 secured to the frame 11, the plate 22 having its lower end returned as shown at 23, to receive the pivoted end of the arm 21 between the plate and the returned portion 23. The arm 21 is offset adjacent to the pivot 24 to provide a shoulder 25 that by engaging the upper edge of the returned portion 23 limits the swinging of the arm 21 on the pivot 24 to hold the arm 21 and to limit its swinging on the pivot. The free end of the arm 21 is provided with a notch 26 that receives the bolt or bar 15 when the arm 21 is in dotted line position as shown in Figure 4, during the closing of the door, and by swinging past the center of gravity to the pivot 24 to the position shown in full lines in Figure 4, holds the door 10 in latched position. To permit the movement of the arm 21 on its pivot and the end thereof to describe an arc with the pivot as its center, the bolt or bar 15 swings slightly in the opening 14 of the L-shaped bracket 12 against the resistance of the spring 18, the resilience of the spring holding the bar in engagement with the notch 26 during said movement. The bolt or bar 15 may also be slid towards the frame 11 and over the headed stud 20, and when in such position the door will be fixedly latched to prevent it being opened from the outside. In opening the door

from the inside, the bolt or bar is used as a hand-hold to push against the door, and when the door is opened the arm 21 will be swung on its pivot 24 outwardly of the frame 11 into the position shown in dotted lines in Figure 4 and in position to be engaged by the bar when the door is released and is closed by the reaction of the spring 19 or other closing means.

In Figures 6, 7, 8 and 9 is shown a modified construction of the latching means, consisting of a bar 30 slidably mounted in the tubular guide 31 on a bracket 32 secured to the door 10, said bolt being engageable in a recess 33 in the frame 11 when the door is closed to fixedly latch the door. Pivotedly mounted on a plate 34 secured to the frame 11 is a pivoted keeper arm 35, said plate being returned as shown at 36, and spaced from the plate to receive the pivoted end of the arm 35, 37 representing the pivot for said arm, and the arm 20 is offset to form a shoulder 38 that engages the edge of said returned portion 36 to limit the swinging of the arm 35 as hereinbefore described in relation to arm 21, and the edge of the returned portion 23. Arm 35 is provided with an angular portion 39 that is substantially parallel with the offset shoulder 38, and the extremity of said angular portion 39 extends inwardly opposite to the arm 35 as shown at 40 and engages the plate 34.

Slidably mounted in the returned portion 38 and the angular portion 39, is a plunger 41, said plunger being preferably made of a strip of metal bent on itself intermediate of its ends as indicated in Figures 6 and 9, and provided with a notch 42 to receive the bolt 30. Plunger 41 has 35 its lower end reduced as shown at 43 and providing shoulders 44 on opposite sides of the reduced portion, to receive the thrust of an expansible coil spring 45 mounted on said reduced portion 43, and terminally engaging the offset portion 38. To 40 limit the movement of the plunger 41 under the impulse of the spring 45, it will be apparent that when the shoulders 44 are alined with the inner side of the angular portion 39 that the angular portion 39 will receive the thrust of the spring, 45 and in addition thereto the extremities of the reduced portion 43 are slightly spread as shown at 46.

In this form of the invention the yielding means

is carried by the pivoted keeper member, arm 35, so as to permit the latch member when in engagement with the bolt 30 to swing on its pivot 37, otherwise the operation of the latch is identical with that hereinbefore described in relation to Figures 1 to 5, inclusive.

It will be apparent that instead of the bolt 15 being tubular that the end of the bolt may be provided with a socket or recess to receive the headed stud 20, and in fact any other means to fixedly latch the door by sliding the bolt into engagement with the keeper may be substituted for that shown and described. Also that other changes may be made in the construction of the device consistent with the hereinafter included claims, so that I do not limit myself to the specific structure as herein stated.

What I claim as my invention is:—

1. A door latch, comprising a keeper member pivotedly mounted on a door frame, a bolt pivotedly mounted on a door and engageable with the free end of said keeper member, and a spring engaging said bolt and holding it in yielding engagement with the keeper member to permit it to swing on its pivot during the opening and closing movements of the door.

2. A door latch as in claim 1, the free end of the keeper member being provided with a notch to engage the bolt.

3. In combination with a swinging door and its frame, brackets secured to the door, a bolt slidably mounted on the brackets and pivotally mounted on one of the brackets, spring means engaging the bolt and another of said brackets and yieldingly holding the bolt from pivotal and sliding movement, and a keeper member pivotally mounted on the frame and engaging the bolt when the door is closed.

4. In combination with a swinging door and its frame, an L-bracket secured to the door, a U-bracket also secured to the door, a bolt slidably mounted on the brackets and pivotally mounted in the L-bracket, a keeper member pivoted on the door frame and having a notch in its free end to receive the bolt when the door is closed, and a spring engaging the bolt and holding it engaged in the notch.

HENRY K. MEIS.
